UNITED STATES PATENT OFFICE.

CHAUNCEY ANIAS MURRAY, OF SUPERIOR, WYOMING.

IDENTIFICATION-TAG.

1,205,103.

Specification of Letters Patent. Patented Nov. 14, 1916.

Application filed February 10, 1916. Serial No. 77,474.

To all whom it may concern:

Be it known that I, CHAUNCEY ANIAS MURRAY, a citizen of the United States, residing at Superior, in the county of Sweetwater and State of Wyoming, have invented certain new and useful Improvements in Identification-Tags; and I do declare the following to be a full, clear, and exact description of the invention, such as will enable others skilled in the art to which it appertains to make and use the same.

My invention is an improved identification tag for numerous kinds of articles, it being shown and described in the present application as applied to a key ring.

The object of the invention is to provide a simply constructed and inexpensive device of the class specified which will not only perform the functions for which it is designed, but which may well be used for other purposes, it being equipped with numerous unique formations for allowing it to be employed for a number of uses.

With this general object in view, the invention resides in certain novel features of construction and in unique combinations of parts to be hereinafter fully described and claimed, the descriptive matter being supplemented by the accompanying drawings which constitute a part of this application and in which:

Figure 1 is a front elevation of the improved device in operative position; Fig. 2 is a similar view with the pivotally mounted latch plate swung in one direction for use as a bottle opener, screw driver, or wrench; Fig. 3 is a similar view with the latch plate moved in the opposite direction for allowing the two sections of the tag to be separated to disclose the name plate therebetween; Fig. 4 is an elevation of the device in open position; Fig. 5 is a longitudinal sectional view taken on the plane indicated by the line 5—5 of Fig. 1; and Fig. 6 is a transverse section as viewed on the plane of the line 6—6 of Fig. 1.

In specifically describing the construction shown in the drawings above briefly described, similar characters will be placed on corresponding parts throughout the several views and reference will be herein made to the numerous elements by their respective indices. To this end, the numerals 1 and 2 designate two flat sections of which the improved tag is constructed, said sec-

tions being in the form of elongated plates formed at one end with hinge knuckles interengaged and connected as shown at 3. The side edges of both sections 1 and 2 are preferably curved as shown to impart a neat and attractive contour to the article, and said edges of the section 1 are provided with longitudinally extending flanges 4 projecting therefrom toward the plate 2, whereby a suitable name plate 5 may be received between said flanges and between the two sections 1 and 2.

The ends of the flanges 4 at the free end of the plate 1 are each formed with a notch 6, and said end of the plate is bent laterally to provide a transverse end flange 7 whose free edge is suitably shaped and bent to form an overhanging claw 8 lying approximately parallel to the inner face of the aforesaid plate 1.

A key ring or the like 9 is provided with an attaching neck 10 having a straight portion hooked under the claw 8 and received in the notches 6, said portion being normally retained in this position by a pair of claws 11 formed by notching the free end of the plate 2, said claws straddling the aforesaid claw 8 and contacting with the outer side of the flange 7 as shown. To retain the parts in this position, the claw 8 is of such dimensions as to allow it to extend beyond the outer face of the plate 2, and a latching plate 12 cooperates with said claw.

The plate 12 lies on the outer face of the plate 2 and is pivoted near one end to said plate 2 adjacent the free end of the latter as disclosed at 13. The pivoted end of the latch plate 12 is normally received between said plate 2 and the overhanging claw 8 as shown clearly in Fig. 1, being held in this position by a boss 14 struck outwardly from the plate 2 and received in a rectangular opening 15 formed in said latch plate. By swinging the plate 12 in one direction a notch 16 with which its pivoted end is provided will be so disposed as to clear the claw 8 as shown in Fig. 3, thus permitting the two sections 1 and 2 to be opened to the position disclosed in Fig. 4. The key ring 9 may now be easily detached for removing keys therefrom or placing others thereon. Also, it will be obvious that opening of the device in this manner displays the name plate 5 by which the owner's name and address may be ascertained.

When the plate 12 is swung in the opposite direction around its pivot, a shoulder 17 with which it is formed abuts the claw 8 and limits the movement of said plate to 5 right-angular relation with the sections 1 and 2. This plate may now be used as a wrench, the opening 15 receiving the object to be turned. Furthermore, said plate 12 may be used as a screw driver or as a bottle 10 opener, its free end being designed for these purposes as shown respectively at 18 and 19. It is to be observed that while using the plate 12 as any kind of a tool, the two sections 1 and 2 coöperate to form an effective 15 handle therefor.

Preferably used in conjunction with the parts above described, is an appropriate spring hook 20 to be hung on the user's belt or upon another appropriate part of his apparel.

From the foregoing, taken in connection with the accompanying drawings, the construction, manner of operation and numerous advantages of the improved device will 25 be readily understood without requiring a more extended explanation. In conclusion, however, I will state that although certain specific details of construction have been shown and described for illustrative purposes, numerous changes may be made within 30 the scope of the invention as claimed without sacrificing the main advantages thereof.

I claim:—

In an identification tag composed of two 35 elongated sections in the form of plates hinged together at one end, longitudinal flanges projecting from the side edges of one plate toward the other plate and adapted to receive a name plate therebetween, the end 40 of said flanges at the free end of the first-named plate being formed with transversely aligned notches to receive a ring, an overhanging claw formed on said free end of 45 said first-named plate to pass in one direction around said ring, a pair of claws formed on the free end of the second-named plate and straddling the first-named claw to pass in the opposite direction around the ring, said first-named claw extending beyond 50 said pair of claws, and a flat latch plate lying against the outer side of said second-named plate and pivoted thereto near the free end thereof, said latch plate having one end received between said second-named 55 plate and the first-named claw, said end of the latch plate having a notch to clear this claw when said plate is turned upon its pivot.

In testimony whereof I have hereunto set 60 my hand in presence of two subscribing witnesses.

CHAUNCEY ANIAS MURRAY.
